(57) **CLAIM**

The ornamental design for a pressing tool for cutting tool, as shown and described.

DESCRIPTION

FIG. 1 is a front view of a pressing tool for cutting tool in accordance with the present design;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a first perspective view thereof;
FIG. 8 is a second perspective view thereof;
FIG. 9 is a first referential view showing the state in use thereof; and,
FIG. 10 is a second view showing the state in use thereof. The broken lines shown in the drawings represent portions of the pressing tool for cutting tool that form no part of the claimed design.

1 Claim, 6 Drawing Sheets
